(57) **CLAIM**

The ornamental design for a hand fidget spinner, as shown and described.

DESCRIPTION

FIG. 1 is a perspective view of a hand fidget spinner;
FIG. 2 is a front elevation view thereof;
FIG. 3 is a right side elevation view thereof, with the left elevation view being a mirror image thereof;
FIG. 4 is a top plan view thereof; and,
FIG. 5 is a bottom plan view thereof.
The broken lines shown in the drawings depict a bearing of the hand fidget spinner and openings that form no part of the claimed design.
